UNITED STATES PATENT OFFICE.

ERWIN E. MILLER, OF FULLERTON, CALIFORNIA.

EXPANSIBLE PACKER FOR PLUNGERS.

Application filed June 12, 1925. Serial No. 36,672.

This invention relates to improvements in plungers for pumps and the like.

An object of the invention is to provide a plunger having a plunger rod on which two heads are mounted, and between which heads there is arranged an expansible packing adapted to be expanded by the fluid pressure.

Another object of the invention is to provide a sealing means for preventing the leakage of fluid between the heads.

A further object of the invention is to provide a pump plunger having a pair of heads between which is arranged an expansible packing adapted to be expanded by the fluid pressure, and to provide a separate means for closing the passages which admit the fluid pressure to the space between the heads and the expansible packing.

With the foregoing and other objects in view which will be made manifest in the following detailed description and specifically pointed out in the appended claims, reference is had to the accompanying drawings for an illustrative embodiment of the invention, wherein:

Figure 1 is a vertical section through a pump barrel or cylinder and through the plunger of the improved construction disclosed therein,

Fig. 2 is a side elevation of the improved plunger,

Fig. 3 is an end elevation of the plunger and may be considered as taken in the direction of the arrow 3 upon Fig. 2,

Fig. 4 is a perspective view of one of the heads,

Fig. 5 is a perspective view of the expansible packing, and

Fig. 6 is a perspective view of the sealing ring.

Referring to the accompanying drawings wherein similar reference characters designate similar parts throughout, the plunger consists of a plunger rod 10 which is tapered, as indicated at 11, and which is provided with a cylindrical threaded end 12. Heads 13 and 14 are arranged upon the plunger rod and have projecting hubs 15 and 16 which abut each other. The heads are maintained upon the plunger rod 10 by means of a nut 17 and a lock nut 18. On the opposed faces of the heads 13 and 14 there are formed annular shoulders 19 and 20. The expansible packing 21, which may be formed of soft, flexible rubber or equiva-

lent material, is disposed between the heads and has its end portions engageable upon and arranged about the annular shoulders 19 and 20. Apertures 22 are formed longitudinally through the heads between the hubs 15 and 16 and their respective shoulders 19 and 20. A sealing ring 23 is disposed about the hubs 15 and 16 and has outwardly extending flanges 24 which bear against the opposed faces of the heads 13 and 14. The sealing ring is preferably formed of soft, flexible rubber or equivalent material, and its flanges 24, because of their resiliency, act as check valves or closures for the inner ends of the apertures 22.

The operation of the plunger is as follows: Upon reciprocation of the plunger, the fluid pressure within the barrel or cylinder of the pump enters through the apertures 22, and escapes past the flanges 24 on the sealing ring 23, filling the chamber 25 and thus expanding the expansible packing 21 against the inferior surfaces of the barrel. The sealing ring 23 prevents leakage of fluid between the abutting surfaces on the hubs 15 and 16, and as it is detached from the expansible packing, any movement of the flanges 24 in opening or closing the apertures 22 in no way interferes with or influences the expansible packing. When the packing 21 is slightly expanded, its end portions will disengage from the exterior surfaces of the shoulders 19 and 20, so that the pressure within the chamber 25 is applied between the shoulders and the packing. This causes the end portions of the expansible packing to bear or expand against the interior surfaces of the pump barrel or cylinder with as great a force as that which is applied at the center of the expansible packing. This is an important feature on plungers of this type for the reason that the outer edges of the expansible packing become chipped and chewed up so that after the packing has been slightly worn, it is difficult to make the end portions of the packing fit snugly against the interior of the barrel. The pressure beneath the end portions of the packing maintains these portions in their expanded or bearing positions.

It will be readily appreciated that this form of plunger can be easily and quickly constructed, the packing 21 being shown merely in the form of a cylindrical ring which can be easily molded. Although the packing 21 is illustrated as being in the form

of a smooth ring, it can be modified if so desired.

It will be understood that various changes in the detail of construction may be made without departing from the spirit or scope of the invention as defined by the appended claims.

I claim:

1. A pump plunger comprising a plunger rod, means providing heads upon the rod, an expandible packing arranged between the heads, means providing passages through which fluid may be admitted between the heads to expand the packing, and a separate ring detached from the packing and spaced therefrom disposed between the heads, said ring having flange portions serving as closures for the passages.

2. A pump plunger comprising a plunger rod, means providing heads upon the rod, an expandible packing disposed between the heads, a sealing ring disposed between the heads, and means providing passages through the heads through which fluid pressure may enter the space between the heads to expand the packing, said sealing ring serving to prevent leakage between the heads and having outwardly extending flanges adapted to close said passages.

3. A plunger for pumps and the like comprising a plunger rod, means providing heads upon the plunger rod having annular shoulders formed on their opposed faces,

an expandible packing disposed between the heads having end portions engageable upon the shoulders, means providing passages whereby fluid pressure may be admitted to the space between the heads, and means providing closures for said passages.

4. A plunger for pumps and the like comprising a plunger rod, means providing heads upon the plunger rod having annular shoulders formed on their opposed faces, an expandible packing disposed between the heads having end portions engageable upon the shoulders, means providing passages whereby fluid pressure may be admitted to the space between the heads, and a sealing ring disposed between the heads for preventing leakage therebetween, said sealing ring having outwardly extending flanges adapted to close said passages.

5. A pump plunger comprising a plunger rod, heads mounted upon the rod having abutting hubs and having annular shoulders formed upon their opposed faces, a sealing ring disposed about the abutting hubs preventing leakage therebetween, an expandible packing disposed between the heads having end portions engageable upon the shoulders, there being passages formed through the heads, and flanges upon the sealing ring adapted to close said passages.

In testimony whereof I have signed my name to this specification.

ERWIN E. MILLER.
